1

Latin name of genus and species of plant claimed: *Rosa hybrida*.

Variety denomination: 'KORpot112'.

STATEMENT REGARDING PRIOR DISCLOSURES BY THE INVENTOR

The first offer for sale of the new variety was January 2021 in Germany and was also shown on Rosa Danica website on January 2021. The first offer for sale of the new variety and the use on the Rosa Danica website was by the inventor or another who obtained the new variety directly or indirectly from the inventor. No plants of the new variety have been sold in this country or anywhere in the world, nor has any disclosure of the new plant been made, more than one year prior the effective filing date of this application, and such sale or disclosure within one year was either derived directly or indirectly from the inventor.

BACKGROUND OF THE INVENTION

The new variety of rose plant of the present invention was created by controlled breeding in 2016 at Offenseth-Sparrieshoop, Germany by artificial pollination wherein two parents were crossed which previously had been studied in the hope that they would contribute the desired characteristics. The female parent (i.e., the seed parent) of the new variety

(57) **ABSTRACT**

A new and distinct variety of miniature rose plant, referred to by its cultivar name, 'KORpot112', is described. The new variety forms in abundance on a substantially continuous basis attractive, yellow-colored blossoms. The vegetation is vigorous and the growth habit is compact. Attractive dark green, semi-glossy foliage is formed. Additionally, the new variety is particularly well suited for growing as distinctive ornamentation in the landscape.

1 Drawing Sheet

2

was an unnamed seedling (not patented). The male parent (i.e., the pollen parent) of the new variety was an unnamed seedling (not patented) resulting from the cross of a different unnamed seedling (not patented) and the 'KORpedia' variety (U.S. Plant Pat. No. 19,638).

5 The parentage of the new variety can be summarized as follows:

unnamed seedling×(different unnamed seedling×
'KORpedia')

The seeds resulting from the above pollination were sown 10 and small plants were obtained which were physically and biologically different from each other. Selective study resulted in the identification of a single plant of the new variety.

The new variety has been found to undergo asexual 15 propagation at Klein Offenseth-Sparrieshoop, Germany by a number of routes such as vegetative cuttings. Asexual propagation techniques in Klein Offenseth-Sparrieshoop, Germany, such as vegetative cuttings, have shown that the characteristics of the new variety are homogeneous, stable, and strictly transmissible by such asexual propagation from one generation to another. Accordingly, the new variety undergoes asexual propagation in a true-to-type manner.

SUMMARY OF THE INVENTION

25 It was found that the new variety of miniature rose plant of the present invention possesses the following combination of characteristics:

- (a) forms attractive, yellow-colored blossoms,
- (b) exhibits a compact growth habit,
- (c) forms vigorous vegetation, and
- (d) forms attractive ornamental semi-glossy foliage.

The new variety well meets the needs of the horticultural industry. It can be grown to advantage as attractive ornamentation in parks, gardens, public areas, and residential landscapes. Accordingly, it is particularly well suited for growing in the landscape. 5

The new variety can be readily distinguished from its ancestors. More specifically, the unnamed seedling seed parent displays a lower petal count compared to the new variety. Additionally, the pollen parent (different unnamed seedling x 'KORpedia') displays a smaller flower size compared to the new variety. Moreover, the new variety can be readily distinguished from non-parental related similar varieties. For example, the 'KORpot055' variety (U.S. Plant Pat. No. 27,246) displays a darker yellow colored flower and exhibits a less glossy foliage compared to the new variety. 10

The new variety has been named the 'KORpot112' variety. 20

BRIEF DESCRIPTION OF THE PHOTOGRAPH

The accompanying photograph shows, as nearly true as it is reasonably possible to make the same in a color illustration of this character, a typical specimen of the new variety and blossoms of the new variety. The illustrated rose plant of the new variety was approximately twelve weeks of age and was grown indoors in a 10.5 cm container on its own 25 roots at Odense, Denmark.

The drawing sheet illustrates a specimen of the plant displaying flowers at varying points of opening.

DETAILED BOTANICAL DESCRIPTION

The chart used in the identification of colors is that of The Royal Horticultural Society (R.H.S. Colour Chart, 2015 edition). The terminology which precedes reference to the chart has been added to indicate the corresponding color in 40 more common terms. The description is based on a one-year-old specimen of the new variety, observed during September, while growing on its own roots in a greenhouse in a one-gallon container in Cochranville, Pa.

Botanical classification: *Rosa hybrida* cultivar KORpot112. 45
Commercial classification: Miniature Rose.

Plant:

Height.—Approximately up to 36.0 cm.

Width.—Approximately up to 30.0 cm.

Habit.—Compact.

Branches:

Stem color.—Commonly near Green Group 143A.

Length.—Main stems: approximately 36.0 cm on average. secondary stems: approximately 15.0 cm on average.

Texture.—Glabrous.

Thorns.—Amount: moderate. young thorns: length is approximately 4.0 mm on average; width is approximately 2.0 mm at point of attachment; and color is commonly near Orange Group 26C.

Leaflets:

Number.—3, 5, and 7.

Shape.—Ovate; apex is acute; and base is rounded.

Arrangement.—Odd-pinnate.

Venation pattern.—Reticulate.

Margin.—Serrate.

Glossiness of upper side.—Semi-glossy.

Texture.—Upper surface: smooth. under surface: smooth.

Size.—Terminal leaflet: length is approximately 4.0 cm on average; width is approximately 2.0 cm on average. lower leaflets: length is approximately 2.3 cm on average; width is approximately 1.5 cm on average. 5-Leaflet leaf: length is approximately 8.0 cm on average; width is approximately 6.0 cm on average.

Foliage:

Young foliage.—Upper surface color: commonly near Green Group 137A with indistinguishable venation. under surface color: commonly a blend of near Yellow-Green Group 147B and Greyed-Orange Group 176C with venation near Yellow-Green Group 146C.

Old foliage.—Upper surface color: commonly near Green Group 139B with indistinguishable venation. under surface color: commonly near Green Group 138B with venation near Green Group 139C.

Petiole.—Texture: upper surface is smooth; under surface is mostly smooth with sparse prickles. upper surface color: commonly near Green Group 137A. under surface color: commonly near Green Group 137B.

Rachis.—Upper surface color: commonly near Green Group 137A. under surface color: commonly near Green Group 137B.

Stipules.—Length: approximately 7.0 mm on average. width: approximately 2.0 mm on average. margin: Entire to erose. upper surface color: commonly near Green Group 137A. lower surface color: commonly near Green Group 138B.

Inflorescence:

Number of flowers.—About 7 blooms on average on a plant at once.

Number of blossoms per stem or in a cluster.—Typically 1 and 2 blossoms per stem on average.

Peduncle.—Color: commonly near Green Group 138A. diameter: approximately 3.0 mm on average. length: approximately 3.0 cm on average. surface texture: glabrous. strength: strong.

Sepals.—Number: 6 upper surface color and texture: commonly near Green Group 138A, covered in short pubescence. under surface color and texture: commonly near Green Group 138A, puberulent. size: length is approximately 1.5 cm on average; width is approximately 1.0 cm on average. margin: entire with extension on two or three sepals measuring 7.0 mm in length and 2.0 mm in width. shape: lanceolate. apex: acute to aristate. base: truncate or flat as it joins the receptacle.

Buds.—Shape: globular. size: length is approximately 2.0 cm on average; width is approximately 2.0 cm on average. color (when opening): commonly near Yellow Group 13A.

Flower.—Form: double, cuplike. profile: flat. diameter: approximately 7.0 cm on average. height: approximately 2.5 cm on average. duration: on the plant approximately 28 days. petal color when first and fully opened: upper surface is commonly near Yellow Group 12A with a basal spot of near White Group 1558; under surface is commonly near Yellow Group 3C with basal spot of near White Group 155B.

petal color when fading: upper and under surfaces are commonly near White Group 155C with hint of White Group 155A. petal texture of upper and lower surfaces: glabrous.

Fragrance.—Very light sweet scent.

Petal.—Number: 93 on average. drop: average for the type. length: inner petals are approximately 1.0 cm on average and outer petals are approximately 2.5 cm on average. width: inner petals are approximately 8.0 mm on average and outer petals are approximately 2.5 cm on average. overall shape: broadly obovate. margin: entire. apex shape: rounded to cuspidate. base shape: rounded to cuneate.

Petaloids.—Number: commonly 5 per flower. color upper and under surfaces: commonly near Yellow Group 13A with a basal spot of near Yellow Group 13B. length: approximately 5.0 mm on average. width: approximately 3.0 mm on average. texture: smooth. margins: variable, entire to erose. shape: rounded and mostly curving inward. apex: round. base: cuneate.

Stamen.—Number: approximately 80. anthers: number is approximately 80; color is commonly near Yellow Group 11C; length is approximately 1.5 mm on average; and shape is oval. filaments: length is approximately 1.5 mm on average and color is commonly near Green-Yellow Group 1B.

Pistils.—Arrangement: separate and free. number: approximately 96. style: length is approximately 5.0 mm and color is commonly near Green-Yellow Group 1B at the base, transitioning to near Red

Group 45A at the apex. stigma: diameter is commonly less than 1.0 mm; shape is fan shaped; and color is commonly near Green-Yellow Group 1B.

Receptacle.—Diameter: approximately 8.0 mm on average. shape: urn shaped. color: commonly near Yellow-Green Group 144A. surface texture: smooth.

Pollen.—None observed.

Hips/seed.—None observed.

Development:

Vegetation.—Dark green, vigorous, and strong.

Blossoming.—Abundant and substantially continuous.

Resistance to diseases.—Good resistance for powdery mildew (*Sphaerotheca pannosa*) disease under normal greenhouse growing conditions in Cochraneville, Pa.

Hardiness.—Unknown.

The new 'KORpot112' variety has not been observed under all possible environmental conditions to date. Accordingly, it is possible that the phenotypic expression may vary somewhat with changes in light intensity and duration, cultural practices, and other environmental conditions.

I claim:

1. A new and distinct variety of miniature rose plant named 'KORpot112' characterized by the following combination of characteristics:

- (a) forms attractive, yellow-colored blossoms,
- (b) exhibits a compact growth habit,
- (c) forms vigorous vegetation, and
- (d) forms attractive ornamental semi-glossy foliage;

substantially as herein shown and described.
